(57) **CLAIM**

The ornamental design for arm for wafer transportation for manufacturing semiconductor, as shown and described.

DESCRIPTION

FIG. 1 is a perspective view of an arm for wafer transportation for manufacturing semiconductor showing our new design; FIG. 2 is a top plan view thereof; FIG. 3 is a bottom plan view thereof; FIG. 4 is a front view thereof; FIG. 5 is a rear view thereof; FIG. 6 is a left side view thereof, the right side view being a mirror image; FIG. 7 is an enlarged sectional view taken along line 7-7 of FIG. 2; and, FIG. 8 is an enlarged sectional view taken along line 8-8 of FIG. 2. The broken lines shown in the drawings represent portions of the arm for wafer transportation for manufacturing semiconductor that form no part of the claimed design.
